UNITED STATES PATENT OFFICE.

EDWARD A. ALLEN, OF RUMFORD FALLS, AND HERBERT I. ALLEN, OF PORTLAND, MAINE, ASSIGNEES TO ELECTRON CHEMICAL COMPANY, OF PORTLAND, MAINE, A CORPORATION OF MAINE.

ELECTROLYTIC CELL.

1,148,274.

Specification of Letters Patent. Patented July 27, 1915.

Application filed January 2, 1914. Serial No. 809,833.

To all whom it may concern:

Be it known that we, EDWARD A. ALLEN and HERBERT I. ALLEN, citizens of the United States, and residents, respectively, 5 of Rumford Falls, in the county of Oxford, State of Maine, and of Portland, in the county of Cumberland and State of Maine, have invented certain new and useful Improvements in Electrolytic Cells, of which 10 the following is a specification.

This invention relates to electrolytic cells, and its object is to provide an improved cell body.

Of the accompanying drawings, which 15 illustrate our invention: Figure 1 represents a perspective view, partly broken away, of a unitary cell body composed of cast concrete. Fig. 2 represents a top plan view of the complete cell body, on a smaller scale. 20 Fig. 3 represents a longitudinal vertical section through the cell body, in the plane indicated by line 3—3 of Fig. 2. Fig. 4 represents an end elevation of the cell body, on a larger scale. Fig. 5 represents a 25 vertical cross section through the cell body and includes the electrodes and means for holding them in place. Fig. 6 represents a perspective view of one end of a two-part cell body, the end portion of the base member being indicated by dotted lines to expose 30 to view the mortised formation of the anode-supporting portion. Fig. 7 represents a perspective view of the end portion which is represented by dotted lines in 35 Fig. 6.

The same reference characters indicate the same parts wherever they occur.

In both forms illustrated by the drawings, the cell body is composed of concrete. 40 Referring more particularly now to the form shown by Figs. 1 to 5, inclusive, the cell body is cast complete in one part, the various portions of which include a base 10, upstanding end portions 11, 11, and a 45 horizontally extending top portion 12 connecting the end portions. These four portions form a substantially rectangular open body and provide an anode chamber 13 which is open at the sides of the body. The 50 base 10 includes a continuous laterally extending flange 14 in which is formed a continuous trough 15 for collecting the caustic soda which drips from the cathodes. The caustic soda is discharged from the trough 55 through a port 16. The top portion 12

which for convenience we term the freeboard, is formed with a series of vertically extending holes 17 which receive the carbon rods 51 by which the anodes 50 are supported in the chamber 13. The holes 17 are 60 elliptic in cross section to provide spaces for the accumulation of chlorin gas. The rods 51 have lateral extensions which rest upon the surface 18. This as shown is below the actual top of the freeboard in consequence of forming a depression in the top of the freeboard. This depression is surrounded on its four sides by flanges 19 and is adapted to receive a suitable plate for supporting the carbon rods which support 70 the anodes. The cathodes, indicated as a whole at 20, 20 in Fig. 5, are held firmly against the sides of the cell body by clamping bars 21, and the cell body is provided with a plurality of horizontally extending 75 transverse holes 22 through which screw-rods 23 may be loosely passed to provide the necessary support for the bars 21. As shown by Fig. 5, the upper screw-rod 23 is secured in place by nuts 24 and washers 80 25 which bear against the freeboard 12, the ends of the rod projecting sufficiently beyond the nuts 24 to receive the clamping bars 21 and clamping nuts 26. The clamping nuts as shown are provided with handles 27 by which they may be set up to force the clamping bars against the cathodes and to force the cathodes in turn against the vertical surface afforded by the base 10, end portions 11 and freeboard 12. 85 It will be observed that the trough hereinbefore mentioned is below and in vertical alinement with the cathodes, where it is adapted to receive the caustic soda which drips from the cathodes. A passageway 30 90 extends downwardly through one end of the freeboard 12 and into one of the upstanding end portions 11 which is for this reason made larger than the other end portion 11. A horizontal passageway 31 (Fig. 100 3) extends from the bottom of the passageway 30 into the anode chamber 14 whereby the brine may be introduced into the anode chamber by being delivered into the top of the passageway 30. We have shown the cell 105 body as being provided with reinforcements in the form of rods. The base 10 is provided with longitudinally extending reinforcing rods 32 and with transversely extending reinforcing rods 33 whose ends are 110

turned upwardly as indicated at 34 to reinforce the flange 14. The end portions 11 are reinforced by vertically extending rods 35, and the freeboard 12 is reinforced by horizontal longitudinally extending rods 36. In each instance the rods are entirely inclosed in the body of concrete so that they will not be exposed at any point to the electrolyte. The several reinforcing rods are 5 arranged so that they will not intersect any of the holes or passageways with which the cell body is provided. As shown by Figs. 2 and 3, the holes 22 which receive the upper screw-rods 23 extend through the vertical partitions which separate the holes 17, the screw-rods being thus isolated from the electrolyte and the gases.

Referring now to Figs. 6 and 7, which illustrate in what manner the cell body may be made in two parts, the structure is substantially the same as that hereinbefore described excepting that the freeboard 12' is not integral with relation to the upstanding end portions. In this form one of the end 10 portions is indicated at 11' and is formed with a horizontal shoulder 40 upon which a complementary shoulder 41 of the freeboard is adapted to rest. Similar shoulders are formed on the other end portion and at 15 the other end of the freeboard. In order to preserve the lateral relation of the freeboard the ends of the latter are provided with vertically extending ribs 42, and the end portions 11' are provided with grooves 43 for 20 the reception of said ribs. The freeboard is thus adapted to be lowered into the desired position relatively to the base and end portions of the cell body. The end portion 11' illustrated is provided with passageways 25 30 and 31 similar to those hereinbefore described, for conducting the brine into the anode chamber.

We claim:

1. An electrolytic cell comprising a cell 45 body having an anode chamber open at the sides of the body, and vertical holes extending from the top to said chamber, and anode-supporting members arranged in said holes, said holes being substantially larger 50 in cross section than said supporting members to provide gas chambers.

2. An electrolytic cell comprising a main body having an anode chamber open at op-

posite sides, anodes arranged in said chamber, cathodes arranged outside said chamber in coöperative relation to the open sides of the latter, and means arranged to fasten 55 said cathodes to said main body, said main body including a concrete base, portions of which base underlie said cathodes and have 60 troughs formed in them to collect whatever liquid drips from the cathodes.

3. An electrolytic cell comprising a top portion, a bottom portion, and end portions, forming an anode chamber open at opposite 65 sides, said top portion having holes extending substantially vertically therethrough to provide gas chambers communicating with said anode chamber, said top portion also having rod-receiving holes extending transversely therethrough, said rod-receiving holes being between said gas chambers, anodes arranged in said anode chamber, cathodes arranged outside said anode chamber in coöperative relation to the open sides 70 of the latter, rods arranged in said rod-receiving holes, and means arranged to coact with said rods to fasten said cathodes in place.

4. An electrolytic cell body comprising a 80 top portion, a bottom portion, and end portions, forming an anode chamber open at opposite sides, said top portion having holes extending substantially vertically therethrough to provide gas chambers, said top 85 portion also having holes extending transversely therethrough between said gas chambers to receive rods for fastening cathodes in place.

5. An electrolytic cell body comprising a 90 base portion and upstanding end portions integral therewith and composed of concrete, and a detachable top portion for supporting the anodes, said end portions and top portions being formed with coöperative 95 top-supporting shoulders and coöperative tongue and groove formations for holding said top portion in place.

In testimony whereof we have affixed our signatures, in presence of two witnesses.

EDWARD A. ALLEN.
HERBERT I. ALLEN.
